UNITED STATES PATENT OFFICE.

CHRISTIAAN W. AVELING, OF ELGIN, ILLINOIS, ASSIGNOR TO JULIA AVELING, OF LOCKPORT, ILLINOIS.

HOISTING MACHINERY.

Application filed January 18, 1919. Serial No. 271,778.

To all whom it may concern:

Be it known that I, CHRISTIAAN W. AVELING, a citizen of the United States, residing at Elgin, in the county of Kane and State of Illinois, have invented new and useful Improvements in Hoisting Machinery, of which the following is a full, clear, concise, and exact description, reference being had to the accompanying drawing, forming a part of this specification.

My invention relates to hoisting machinery, and, more particularly, to hoisting machinery for use with a grab-bucket.

One of the objects of my invention is to provide an improved construction in which a single motor will control both the opening and the closing of the bucket and also the hoisting and lowering thereof.

A further object of my invention is to provide an improved construction which will be extremely simple, light, and compact, and which will be durable and efficient in use.

Further objects will appear from the detailed description to follow, and from the appended claims.

In the drawings, in which one embodiment of my invention is shown—

Figure 1 represents a plan view, partly in section, of a trolley-hoist embodying my invention;

Fig. 2 is a side elevation of Fig. 1;

Fig. 3 is a section on the line 3—3 of Fig. 1;

Fig. 4 is a section on the line 4—4 of Fig. 1;

Fig. 5 is a perspective view of a helical cam forming part of the holding brake mechanism; and

Fig. 6 is a perspective view of a collar forming part of the delayed-action mechanism.

In my invention I provide a construction whereby a single motor controls both the lacing rope and the holding rope; I accomplish this result by providing delayed-action mechanism, whereby the drum which controls the lacing rope can be given a predetermined amount of rotation before the drum which controls the holding rope is caused to rotate at all. Thus, the drum which controls the lacing rope can be given a sufficient amount of rotation to close the grab-bucket, after which, by means of the delayed-action mechanism, the drum which

controls the holding rope will be put in operation and both ropes together will then operate to hoist the bucket. Similarly, in dumping the bucket, the drum which controls the lacing rope can be given a predetermined amount of rotation before the drum which controls the holding rope is caused to rotate at all, so that the holding rope will hold the bucket in position while the lacing rope is slackened up sufficiently to permit the contents of the bucket to be dumped. After the bucket is dumped, the delayed-action mechanism comes into operation to cause the drum which controls the holding rope to operate, and after that both drums are rotated together to permit the bucket to be lowered.

Referring now to the drawings in detail, the hoisting mechanism shown comprises a hoisting trolley 10 (shown as mounted to travel on a track 11), and a grab-bucket 12 which may be of any usual type and is controlled by means of the lacing rope 13 and the holding rope 14.

The lacing rope 13 controls the opening and closing of the grab-bucket, and the holding rope 14 assists in raising and lowering the bucket and holds it in position while the lacing rope 13 is slackened to permit the contents of the bucket to be discharged. A certain definite movement of the lacing rope 13 is necessary both in opening and in closing the bucket. Thus, assuming that the bucket is open and it is desired to close it and hoist the bucket, the lacing rope 13 would be wound up a certain distance, the holding rope 14 meantime not being wound up until the grab-bucket is closed, after which both the lacing rope 13 and the holding rope 14 will be wound up to hoist the bucket.

Similarly, assuming that the loaded bucket has been raised to the position where it is desired to dump it, the lacing rope 13 is unwound a certain definite amount, sufficient to permit the grab-bucket to open, the holding rope 14 meantime not being unwound at all, until the bucket is completely opened, after which both the lacing rope 13 and the holding rope 14 are unwound, permitting the grab-bucket to be lowered. Grab-buckets which can be thus operated are old in the art and need not be described in detail.

Referring now in detail to the hoisting trolley, this comprises a carriage 15 mount-

ed to travel on the track 11, a lacing drum 16 for controlling the lacing rope 13, a holding drum 17 for controlling the holding rope 14, a hoist-motor 18 for controlling both the 5 lacing drum 16 and the holding drum 17, transmission means 19 between the motor 18 and the lacing drum 16, and delayed-action transmission means 20 between the lacing drum 16 and the holding drum 17, and holding-brake mechanism 21 for holding the grab-bucket while the lacing rope is slackened to permit the bucket to be dumped.

The lacing drum 16 is secured to rotate with the lacing-drum shaft 22 which is rotatably mounted in suitable bearings 23, 15 24, and 25. The holding drum 17 is secured to rotate with the holding-drum shaft 26 one end of which is mounted in suitable bearings 27 and 28 of the trolley side, and 20 the other end of which is journaled in a sleeve 29 (which sleeve forms part of the transmission 19 between the hoist-motor and the lacing drum 16).

The transmission 19 between the motor 18 25 and the lacing drum 16 comprises a motor-pinion 30, a large gear 31 meshing with the motor-pinion 30 and secured to rotate with the sleeve 29 (previously referred to), a pinion 32 which may be formed integral 30 with the sleeve 29, and a large gear 33 meshing with the pinion 32 and keyed to the lacing-drum shaft 22.

Before describing the delayed-action transmission between the lacing drum 16 35 and the holding drum 17, I shall first describe the holding-brake mechanism 21. This comprises a ratchet-wheel 34 controlled by a pawl 35 (Figs. 1 and 3), which ratchet-wheel can rotate in the winding direction of the holding drum 17 but cannot rotate in the unwinding direction; a 40 brake-disk 36 secured to rotate with the holding-drum shaft 26 (the ratchet-wheel 34 and the brake-disk being provided with co-operating braking surfaces); a combined 45 brake-disk and gear 37 (said brake-disk and ratchet-wheel 34 having co-operating braking surfaces); and a helical cam 38 rotatable with the shaft 26 and having a helical face 50 for engagement with a corresponding helical face on the hub of the brake-disk 37.

The pawl 35 is thrown into engagement with the ratchet-wheel 34 on unwinding movement of the holding drum 17, and is thrown out of engagement with the ratchet-wheel 34 on winding-up movement of the holding drum 17, by means of a friction collar 40 (Figs. 1 and 3) which frictionally engages the hub of the brake-disk 36 and 55 which is connected with the pawl 35 by means of a link 41 pivotally connected to the collar 40 at 42, and pivotally connected at its other end at 43 to an arm 44 which may be formed integral with the hub of the pawl 60 35, the hub of this pawl being pivotally

mounted on a pin 45. The collar 40 is frictionally held in engagement with the hub of the brake-disk 36 by means of a pair of springs 46 arranged to draw the mating sections of the collar 40 into snug 70 engagement with the hub.

The inclination of the helical cam 39 is such that a downward force exerted on the holding rope 14 will force the helical cam 39 tightly into engagement with the corresponding helical surface of the hub of the brake-disk 37, forcing the latter tightly over against the braking surface of the ratchet 34 and pinching the ratchet-wheel 34 tightly between the brake-disks 36 and 37. As the ratchet 34 cannot rotate in a direction corresponding to an unwinding movement of the holding drum 17, it will hold the holding drum against rotation due to any downward pull on the holding 85 rope 14.

The delayed-action transmission between the lacing-drum shaft 22 and the holding-drum shaft 26 comprises an externally-threaded sleeve 47 feathered on the lacing-drum shaft 22, as indicated at 47¹, a collar 48 adjustably secured to the sleeve 47 and having a shoulder 49 on its face (Figs. 1 and 6) for engagement with a corresponding shoulder 50 on the hub of a gear 51 (the gear 51 being internally threaded for engagement with the external thread on the sleeve 47), a collar 52 similar to the collar 48 adjustably secured on the externally-threaded sleeve 47 and having a shoulder 53 on one face for engagement with a corresponding shoulder 54 on the hub of the gear 51, and the combined brake-disk and gear 37 previously referred to.

I will now describe the operation of the delayed-action transmission, as this description at this stage may make clearer the construction. The purpose of the delayed-action transmission is to permit a predetermined amount of rotation of the lacing-drum shaft 22 before any rotation of the holding-drum shaft 26 is effected. Assuming, then, that the motor 18 is put in operation to cause rotation of the lacing-drum shaft 22, this will cause a corresponding rotation of the externally-threaded sleeve 47, which will, as a result, cause the sleeve 47 to thread itself through the internally-threaded hub of the gear 51. As the lacing-drum shaft 22 continues to rotate, the sleeve 47 continues to thread itself through the hub of the gear 51 until the shoulder 49 comes into engagement with the shoulder 50 on the hub of the gear 51. When this takes place, it causes the gear 51 to rotate with the collar 49 and shaft 22 and as a consequence causes the combined brake-disk and gear 37 to rotate.

Assuming that the lacing drum 16 is rotating in a winding-up direction, the rotation of the combined brake-disk and gear 120

37 will be such as to force the helical face of the hub of this gear into engagement with the helical cam 39, thus wedging the braking surface of the brake-disk 37 over against the braking surface of the ratchet-wheel 34 and pinching the ratchet-wheel 34 between the braking surfaces of the brake-disks 36 and 37. As a result, the combined brake-disk and gear 37, the ratchet-wheel 34, the 10 brake-disk 36, and the holding-drum shaft 26 will all rotate together. A continued rotation of the lacing-drum shaft 22 will thus cause a corresponding rotation of the holding-drum shaft 26 and both the lacing rope 13 and the holding rope 14 will be wound up to raise the grab-bucket 12.

Similarly, assuming that the grab-bucket is full and is in raised position and it is desired to dump it and then lower it, the 20 motor 18 is put into operation in a direction to cause an unwinding movement of the lacing drum 16. This will cause a corresponding rotation of the externally-threaded sleeve 47 which, as a result, will start to 25 thread itself through the internally-threaded hub of the gear 51. The sleeve 47 will continue to thread itself through the hub of the gear 51 until the shoulder 53 of the collar 52 comes into engagement with the 30 shoulder 54 of the hub of the gear 51. However, when the engagement of the shoulders 53 and 54 takes place, a continued rotation of the sleeve 47 and the collar 52 will cause a corresponding rotation of the gear 51 to 35 cause a movement of the gear 37 in a direction the reverse of the winding-up movement of the holding drum 17.

The inclination of the helical cam 39 is such that the just-described rotation of the 40 gear 37 will cause the helical face of the hub of the gear 37 to draw away from the helical cam 39, which will permit the brake-disks 36 and 37 to release their hold on the ratchet-wheel 34 and permit the holding drum 17 to rotate in a direction to allow the grab-bucket 12 to be lowered by its own weight.

The rotation of the lacing drum 16 which takes place prior to the rotation of the holding drum 17 is just sufficient to permit the grab-bucket 12 to open properly to discharge its contents, after which both drums rotate together to lower the bucket. Similarly, in hoisting, the rotation of the lacing drum 16 which takes place prior to the rotation of the holding drum 17 is just enough to properly close the grab-bucket, after which both the lacing drum 16 and the holding drum 17 are rotated to raise the grab-bucket. 55 The amount of rotation of the lacing drum 16 which takes place prior to the rotation of the holding drum 17 may be controlled by adjusting the collars 48 and 52 on the sleeve 47, for which purpose the collars 48 and 52 60 have threaded engagement with the thread-

ed collar 47 and may be held in various positions of adjustment thereon by means of the keys 55.

Up to the time the engagement of the shoulders 53 and 54 takes place, the holding drum will be held against movement by the pawl 35 which will be thrown into engagement with the ratchet 36 by the first slight backward rotation of the holding drum shaft 26, as previously described. This 70 holds the holding drum against downward movement, as any downward pull on the holding rope simply jams the combined gear and brake member 37, over against the ratchet brake wheel 34, causing the 75 ratchet wheel 34 to be clamped firmly between the members 36 and 37, thus holding the holding drum shaft 26 against rotation.

The operation of the transmission mechanism 19 between the motor 18 and the lacing-drum shaft 22 is as follows: The motor-pinion 30 drives the large gear 31, which causes the sleeve 29 to rotate and with it the pinion 32 which drives the large gear 33 keyed to the lacing-drum shaft 22. As 80 previously stated, the holding-drum shaft 26 is journaled in the sleeve 29 which connects the large gear 31 and the pinion 32, and this sleeve 29 is in turn journaled in a suitable bearing 56 in the trolley-side. 85

Any suitable magnetic brake 57 may be provided for the motor 18. This magnetic brake is thrown on automatically when the current is shut off from the hoist motor, in the usual manner of magnetic brakes. This 90 of course holds the lacing drum 16 against movement when the current is shut off from the motor, and prevents the bucket from dumping before the operator is ready, that is, before he reverses the motor to unwind the lacing rope.

By my improved construction I avoid the necessity of separate motors for the holding-drum and lacing drum, and secure an extremely light and compact construc- 100

110 The gear 51 is held against sidewise movement in either direction by means of two cup-shaped members 57 and 58, respectively, one on either side of said gear and having portions abutting the web of said gear to hold the gear in position. These cup-shaped members may be used to form an oil reservoir to keep the enclosed parts bathed in oil.

I claim as new and desire to secure by 120 Letters Patent of the United States:

1. A hoisting machine comprising a releasable grasping device, two drums for controlling the operation of said grasping device, one of said drums serving as a lacing-drum to control the grasping and releasing of said device, and the other drum serving as a holding drum when the grasping device is being released, a single motor for controlling both of said drums, means including a de- 125 130

layed action transmission whereby said lacing drum may be operated without operating said holding drum to cause the grasping and releasing operations, and an automatically acting brake for holding said holding drum against movement when the lacing drum is releasing the load-grasping device.

2. A hoisting machine comprising a releasable grasping device, two drums for controlling the operation of said grasping device, one of said drums serving as a lacing drum to control the grasping and releasing of said device, and the other drum serving as a holding drum when the grasping device is being released, a single motor for controlling both of said drums, means including a delayed action transmission whereby said lacing drum may be operated without operating said holding drum to cause the grasping and releasing operations, and an automatically acting brake for holding said holding drum against movement when the lacing drum is releasing the load-grasping device, and means whereby said automatic brake will be released after the load-grasping device has been released, to permit the holding drum to be operated to lower the load-grasping device.

3. A hoisting machine comprising a releasable load-grasping device, two drums for controlling the operation of said grasping device, one of said drums serving as a lacing drum to control the grasping and releasing of said device, and the other drum serving as a holding drum when the grasping device is being released, a single motor for controlling both of said drums, means including a delayed action transmission whereby said lacing drum may be operated without operating said holding drum to cause the grasping and releasing operations, and an automatically acting brake concentric with said holding drum for holding said holding drum against movement when the lacing drum is releasing the load-grasping device.

4. A hoisting machine comprising a releasable grasping device, two drums for controlling the operation of said grasping device, one of said drums serving as a lacing drum to control the grasping and releasing of said device, and the other drum serving as a holding drum when the grasping device is being released, a single motor for controlling both of said drums, means including a delayed action transmission whereby said lacing drum may be operated without operating said holding drum to cause the grasping and releasing operations, and an automatically acting brake for holding said holding drum against movement when the lacing drum is

releasing the load-grasping device, said brake comprising a member which rotates on the raising movement of the holding drum and is automatically held against movement on the lowering movement of the holding drum, having an impositive connection with the holding drum.

5. A hoisting machine comprising a releasable grasping device, two drums for controlling the operation of said grasping device, one of said drums serving as a lacing drum to control the grasping and releasing of said device, and the other drum serving as a holding drum when the grasping device is being released, a single motor for controlling both of said drums, means including a delayed action transmission whereby said lacing drum may be operated without operating said holding drum to cause the grasping and releasing operations, and an automatically acting brake for holding said holding drum against movement when the lacing drum is releasing the load-grasping device, said brake comprising a member which rotates on the raising movement of the holding drum and is automatically held against movement on the lowering movement of the holding drum having an impositive connection with the holding drum and with the motor.

6. A hoisting machine comprising a releasable grasping device, two drums for controlling the operation of said grasping device, one of said drums serving as a lacing drum to control the grasping and releasing of said device, and the other drum serving as a holding drum when the grasping device is being released, a single motor for controlling both of said drums, means including a delayed action transmission whereby said lacing drum may be operated without operating said holding drum to cause the grasping and releasing operations, and an automatically acting brake for holding said holding drum against movement when the lacing drum is releasing the load-grasping device, said brake comprising a member rotatable with the holding drum on the raising movement and automatically held against rotation on the lowering movement of the holding drum, friction means between the held member and the holding drum for preventing movement of the holding drum during dumping of the bucket and means whereby said frictional holding means are released by continued lowering movement after the bucket is dumped.

In witness whereof, I have hereunto subscribed my name.

CHRISTIAAN W. AVELING.
